United States Patent Office.

WILLIS S. BRONSON, OF HARTFORD, CONNECTICUT.

Letters Patent No. 77,444, dated May 5, 1868.

IMPROVEMENT IN BASE-BURNING STOVES.

The Schedule referred to in these Letters Patent and making part of the same.

TO ALL WHOM IT MAY CONCERN:

Be it known that I, WILLIS S. BRONSON, of the city and county of Hartford, and State of Connecticut, have invented certain new and useful Improvements in Magazine or Reservoir Coal-Stoves; and to enable others skilled in the art to make and use the same, I will proceed to describe its construction and operation, by referring to the drawings, in which the same letters indicate like parts in each of the figures.

The nature of this invention will be understood from the specification and drawings.

The object desired to be attained thereby is to combine utility with durability, cheapen the manufacture, economize fuel, and render it ornamental and attractive in its appearance.

In the accompanying drawings—

Figure 1 is a side elevation.

Figure 2 is a sectional side elevation.

Figure 3 is a top view of a double-movable damper.

Figure 4 is a section showing a modified form of constructing the magazine or reservoir, with the hot-air and smoke-flues.

Figure 5 shows an end view of the same.

a is the base or ash-pit of the stove.

b is the outer wall or body of the stove.

c is a double-ventilated top to the body or hot-air chamber of the stove, which covers the combustion-chamber, and surrounds and holds the magazine or reservoir.

d is a coal-magazine or reservoir, held and supported just above its base by a double-ventilated top, *c*, which covers the combustion-chamber.

e e are smoke and hot-air-conducting flues, formed by the double damper *g*.

f are perpendicular smoke and hot-air-conducting tubes, which connect the hot-air chamber *b'* with the smoke and hot-air-circulating flues *e e*, formed by the double-movable damper *g*. This connection is formed by apertures through the double-top plate *c*, and through the bottom plate of flues *e e*.

g is a double-movable damper and flue-dividing plate, which covers and uncovers two apertures, used for filling the magazine or reservoir, and also forming a flue, through which the smoke and heat pass into the exit or smoke-pipe *i'* when shoved back in place.

This double damper, *g*, is open at each end, so that when pushed back by the rod *h*, all communication with the exit-pipe *i'* is thus cut off, except as it passes through said damper from front to rear, thus distributing the hot air sufficient to heat the oven *k* evenly, which is located directly over the smoke and hot-air-circulating flues *e e*. This position of the damper also closes both openings used for filling the magazine or reservoir, and when said double damper is pulled forward by the rod *h*, the apertures are opened, through which the magazine or reservoir may be filled, and the course of the flues is changed by the same movement of the damper from the front to the back of the stove, and of the exit-pipe *i'*.

Thus it will be seen that when the double damper is pulled forward or pushed back, it will fix and regulate the smoke and hot-air flues of the stove, and this is all accomplished by one motion of the rod *h*.

k is a baking-oven, located directly over the hot-air-circulating flues and double damper, and is heated by means of the emission of heat into said oven from the former-described smoke and hot-air-circulating flues.

l is a cover to said oven.

The plate *o*, in connection with the outer wall of the stove and fire-pot *o'*, serves the triple purpose of forming a base or support of the fire-pot *o'*, and also forming a dead or non-circulating hot-air chamber between the outer surface of the fire-pot and the outer wall, thereby enabling me to burn the coal at much less temperature and less powerful combustion than can otherwise be obtained, and also form a division between the ash-pit *a* and hot-air-chamber *b'*.

The valves *p*, two or more in number, are arranged to open and close apertures in the plate *o*, and are for the purpose of allowing the dust to escape from the base or ash-box produced by shaking the grate.

The double and ventilated top *c*, before referred to, is cast or made of two thicknesses of metal, with open air-space between said plates to prevent it from becoming intensely heated on the outside. The openings *m* are for the induction of air, and the openings *n* are for the excretion of air, the shape of which may be conical, or other desired shape.

n' is a door of access to the fire.

n'' are illuminating-openings in the double top *c*.

n''' are illuminating-openings formed in or through the body of the stove.

The body of the stove is susceptible of great variation of shape and configuration. The same may be said with reference to the whole stove.

The coal-magazine or reservoir is made in one, two, or more parts, and with tubes *f*, and secured together by flanges, or other proper means, and supported by the double-ventilated top *c*, near or just above its lower end, and steadied at the top by the bottom plate of the smoke and hot-air-circulating flues *e e*, thus supporting an unbroken column of coal from the top of the magazine or reservoir to the fire-pot.

I believe I have thus shown the nature, construction, and advantage of this invention, so as to enable others skilled in the art to make and use the same therefrom.

I am aware that attempts have been made to effectually introduce the use of ovens into parlor or base-burning stoves.

What I claim, therefore, and desire to secure by Letters Patent, is—

1. The double-ventilated top *c*, which covers the combustion-chamber *b'*, and forms a support for the magazine or reservoir *d*, substantially as and for the purpose described.

2. I claim, in combination with the double-ventilated plate *c*, and magazine *d*, the conducting-tubes *f* and double-movable damper, and dividing-flue plates *g*, substantially as and for the purpose described.

3. I claim the arrangement of the oven *k*, directly over and in combination with the double-movable damper and dividing-flue plates *g*, substantially as and for the purpose described.

4. I claim the double-movable damper and dividing-flue plate *g*, arranged in and forming the smoke and hot-air flues *e e*, substantially as and for the purpose described.

WILLIS S. BRONSON. [L. S.]
